UNITED STATES PATENT OFFICE.

RAYMOND C. BENNER, OF FREMONT, OHIO, ASSIGNEE TO NATIONAL CARBON CO. INC.,
A CORPORATION OF NEW YORK.

DEY CELL.

Application filed May 18, 1921. Serial No. 470,876.

To all whom it may concern:

Be it known that I, RAYMOND C. BENNER, a citizen of the United States, residing at Fremont, in the county of Sandusky and State of Ohio, have invented certain new and useful Improvements in Dry Cells, of which the following is a specification.

This invention relates to dry cells and has special reference to improvements in that type in which the anode elements are substantially plane and the assembled cell has flat exterior surfaces.

It is an object of my invention to simplify the construction of flat cells and to secure the most compact form consistent with the greatest efficiency. Further objects are to provide novel bag type cells especially adapted to heavy service and to retention in inactive condition until it is desired to energize them.

Other objects and advantages of the invention will be apparent from the appended detailed description of preferred embodiments, illustrated in the accompanying drawings in which—

Fig. 1 is a front elevation of a dry cell constructed according to my invention;

Fig. 2 is a vertical transverse section on line II—II of Fig. 1;

Fig. 3 is a front elevation of a flat bag type cell;

Fig. 4 is a vertical transverse section on line IV—IV of Fig. 3;

Fig. 5 is a vertical transverse section 35 through a flat cell of the general type of that shown in Fig. 4, but having a tight-fitting jacket;

Fig. 6 is a view similar to Fig. 4, and showing the cell in inactive condition;

Fig. 7 is a vertical transverse section 40 through a deferred action cell of somewhat modified form;

Fig. 8 is a perspective view of a carbon electrode;

Fig. 9 is a vertical transverse section 45 through a cell containing an electrode of the type shown in the preceding figure.

Fig. 10 is a view similar to Fig. 9, showing the use of the electrode in another form of cell.

Referring to Figs. 1 and 2, reference numeral 1 denotes flat rectangular plates of zinc, or other suitable electropositive metal,

which form the side walls of the cell. Spacing sheets 2, of pulpboard or other suitable bibulous material, separate the rectangular mix bobbin 3 from the zinc plates. The sheets 2 are coated with paste on the side which rests against the zinc. A carbon electrode 4, which may be of any desired type, but is shown here as a small pointed rod having a brass cap, is embedded in the mix. The mix may contain sufficient excitant fluid to activate the cell.

To secure the assembled elements together, a cementing material 5 is applied around the entire perimeter of the cell and covers the exposed edges of the plates 1, spacing sheets 2 and mix 3. The material used for this purpose should be impervious to moisture, inert to the electrolyte, and should possess sufficient tenacity to hold the assembled parts securely together. Among the materials having these characteristics, I have found that celluloid cement (celluloid dissolved in a volatile solvent) gives good results. It may be conveniently applied to the cell margins by spraying, painting, dipping, or the like, and effectually holds the cell together, while preventing evaporation of moisture from the electrolyte solution. If desired, the edges of the assembly may be bound with cloth or paper before applying the waterproofing material.

In Figs. 3 and 4 is illustrated a cell constructed in general along the line followed in the cell of Figs. 1 and 2, but illustrating an adaptation of the invention to flat cells of the bag type. Referring to Figs. 3 and 4, the zinc plates 6 are depressed or recessed to form the chambers 7 having the filling openings 8. A lining 9, of cloth or other suitable material, is secured to the flat marginal portions of the zinc plates 6 with waterproof cement. The linings 9 space the zinc plates from the mix bobbin 3. The bobbin may be wrapped with fabric, if desired, instead of securing the linings 9 to the zinc plates. The elements are fastened together, as before, by means of cementing material 5. The openings 8, however, are not covered by the material and through them the excitant paste is supplied, preferably after the parts are assembled. The chambers 7 should not be completely filled, so that on heavy service expansion due to

the rapid evolution of gas or other causes may not force the paste from the cell or cause leakage in other ways. In cells of the kind illustrated, the paste chambers may be safely filled to about four-fifths of their capacity. If the cells are to stand for a considerable time before use, the small openings 8 may be sealed in any suitable way to prevent loss of moisture, or a flexible waterproof material may be flowed over the paste surface in the chambers 7. The walls of the chambers may be reinforced or corrugated to increase their rigidity.

The construction shown in Fig. 5 in general follows that just described, but as an additional element a tightly fitting jacket 10, of a material which will shrink on drying, is provided. This material may advantageously be chipboard. The wet jacket is placed about the cell and on drying shrinks and binds the parts tightly together. The waterproof material 5' is preferably applied to the whole exterior of the cell, instead of marginally only, so as to provide a smooth surface of contact for the shrunk jacket. Waterproof paper or similar material may be substituted for the coating of waterproof material 5'. The paper wrapping and jacket are of course, equally applicable to the type of cell shown in Figs. 1 and 2. A paper cap 11 may be placed at the bottom of the cell and the chipboard jacket may be extended at the other end, so as to form an annular recess to receive a seal of plastic material 12.

Fig. 6 illustrates a flat cell of the deferred action type. The construction is the same as for the cell shown in Figs. 3 and 4, but instead of supplying excitant paste to the chambers 7, a dry paste-forming material is placed therein and the mix bobbin is also inserted in substantially dry condition. As the cell contains no moisture, it does not deteriorate through premature electrolytic action or other causes, and may be kept for as long as desired without change.

The mix may be wrapped in absorbent paper or the like and the cloth linings 9 may then be omitted, if desired. The paste forming material may be of any suitable type and is preferably placed in the recesses 7 before the cell is assembled. I prefer to use a dry granular material of the kind described in the United States Patent of R. C. Benner and H. F. French, No. 1,481,178, issued January 15, 1924, as such material permits the water or electrolyte solution to percolate rapidly throughout its mass and substantially immediate activation is obtained. Liquid will be poured into the paste chambers through the openings 8, when it is desired to activate the cell.

In Fig. 7 is shown a deferred action cell operating upon the principle just described, but having its electrodes so disposed that series connection may be made by merely pil-

ing the cells one upon the other. In this type, a flat body of depolarizing mix is molded about a carbon block 11', having a narrowed portion 11'' which protrudes from the side of the mix and is adapted to serve as the carbon pole of the cell. A fiber of llar 12' is placed around the portion 11'' and a pulpboard spacing sheet 13 suitably cut away to receive the collar, rests against the surface of the mix. A sheet 14 of metal overlies the spacing sheet 13. Against the other side of the mix a second spacing sheet 15 is placed. Resting against this latter sheet is a recessed zinc plate of the kind previously described. Waterproof coating and cementing material 5 is applied to the exposed ends of the assembled elements. The chamber 7 contains paste forming material and is activated by addition of water or electrolyte solution through opening 8.

A novel form of carbon electrode, suitable for use with the cells described, except that form shown in Fig. 7, is illustrated in Figs. 8, 9 and 10. The electrode consists of a flat rectangular carbon block 16, having an integral cylindrical lug 17 projecting from one end and adapted to serve as the carbon terminal of the cell. A brass cap 18 may be fitted on the lug. Fig. 9 shows in cross section a flat cell, of the type illustrated in Figs. 1 and 2, having an electrode of this kind with an associated body of mix 19. The internal resistance of the cell is considerably reduced by providing a carbon electrode having an area substantially equal to that of the zinc and the short circuit amperage is therefore increased. Fig. 10 shows the flat electrode embodied in a cell with recessed zincs, of the type previously described.

Instead of coating the exposed edges of the assembled parts with cementing material, waterproof paper or fabric may be stretched over the edges and secured with adhesive. The methods of assembling described are applicable also to cells having a contour different from that illustrated, for example, flat circular cells. Various other modifications and alternative arrangements may be made within the scope of the appended claims.

I claim:

1. In a dry cell, a flat mix bobbin, spacing sheets of bibulous material on opposite sides of the mix and in contact with its entire lateral surface, metal plates abutting upon the spacing sheets, and cementing material retaining the elements together.
2. In a dry cell, a flat mix bobbin, spacing sheets of bibulous material on opposite sides of the mix and in contact with its entire lateral surface, metal plates abutting upon the spacing sheets, and celluloidal material retaining the elements together.
3. In a dry cell, a flat mix bobbin, recessed zinc electrode plates, spacing sheets

- separating the plates from the bobbin, and activating material in the recesses of the plates.
4. In a dry cell, a flat mix bobbin, recessed zinc electrode plates, spacing sheets separating the plates from the bobbin, activating material in the recesses of the plates, and waterproof cementing material securing the elements together.
- 10 5. In a dry cell, a flat mix bobbin, zinc electrode plates having recesses adapted to receive activating material, and spacing sheets separating the plates from the bobbin, said plates having openings permitting the supplying of activating material to the recesses.
- 20 6. In a dry cell of the flat type, an anode, a cathode comprising a flat mix bobbin, spacing means for the anode and cathode, and a jacket having a shrink fit with the anode and cathode and tending to retain them in assembled position.
- 25 7. In a deferred action cell, a flat mix bobbin, recessed zinc electrodes adjacent thereto but spaced therefrom, paste forming
- material in the electrode recesses, and means for supplying activating fluid to said material.
8. In a deferred action cell, a flat mix bobbin, recessed zinc electrodes adjacent thereto but spaced therefrom; paste forming material in the electrode recesses, said electrodes having an opening for supplying activating fluid to said material.
9. In a deferred action cell, a flat mix bobbin, recessed zinc electrodes adjacent thereto but spaced therefrom, dry granular paste forming material in the electrode recesses, and means for supplying activating fluid to said material.
10. In a dry cell, a metal electrode, a carbon electrode having an area not substantially less than that of the metal electrode, a depolarizing mix about the carbon electrode, spacing means separating the metal electrode and the mix, and cementing material securing the assembly together.

In testimony whereof, I affix my signature.

RAYMOND C. BENNER.
